UNITED STATES PATENT OFFICE.

PROKOP J. PROKOP, OF NEW YORK, N. Y.

KINETOSCOPE-FILM MAGAZINE.

1,188,990.

Specification of Letters Patent. Patented June 27, 1916.

Application filed March 17, 1916. Serial No. 84,808.

To all whom it may concern:

Be it known that I, PROKOP J. PROKOP, a subject of the Emperor of Bohemia, and a resident of New York, in the county of New York and State of New York, have invented 5 certain new and useful Improvements in Kinetoscope-Film Magazines, of which the following is a specification.

My invention relates to the re-wind magazines of motion picture projectors, and the main object thereof is to provide such a magazine from which the film may be fed into the projector for another projection without the necessity for the intermediate reverse winding now common, thereby saving 15 much time and greatly reducing the wear on the film.

My invention is fully described in the following specification, of which the accompanying drawings form a part, in which like characters refer to like parts in each of the views, and in which:—

Figure 1 is a front view, partly broken away, of a magazine constructed in accordance with my invention; Fig. 2 is a section taken on the line 2—2 of Fig. 1; Fig. 3 is an enlarged fragmentary view of a detail; and Fig. 4 is an enlarged fragmentary section taken on the line 4—4 of Fig. 1.

Referring to the drawings, 5 represents a circular casing having a raised portion 6, in the form of a sector of a circle, upon one face thereof, this portion 6 being slotted at 7 and being of a slightly greater depth than 25 the width of a motion picture film, and the casing 5 is likewise of a depth slightly exceeding the width of the film, thereby making the casing 5 and raised portion 6 jointly of more than double the width of the film.

Carried in a small casing 8 at the opposite face of the casing 5 is a shaft 9 having a pulley 10 thereon and connected with a film carrier drum 11 within the casing 5 and of only slightly less diameter, the connection 45 between pulley 10 and shaft 9 being by means of a friction clutch 12, the said pulley being driven by a belt 13 connected with the re-wind pulley of a projector upon which my magazine is adapted to be removably 55 mounted in any desired manner, this not being illustrated as it forms no part of the invention.

Within the casing 5 is an immovable central support 14 for a plurality of radially arranged telescopic arms 15, shown as 5 in number but a greater number of which will

preferably be used, each of said arms being maintained in extended condition by means of a contained spiral spring 16, and I provide a roller 17 at the end of each arm. Two 60 of these arms 15, at the sides of the raised portion 6 of the casing, are joined by means of toggles 18 desired ones of which are guided on radial rods 19 to maintain the same in operative relationship, as well as 65 radial fingers 20 carried by the respective toggles 18, these fingers being joined at their outer ends by flexible strips 21. As shown in Figs. 2 and 4, these fingers 20 carry, each, two bars 22 and 23 parallel with each other 70 and with the perimeter of the casing, the outer series of these bars being joined by a fabric strip 24 and the inner by a fabric strip 25, these strips jointly forming a channel open at its inner edge for the reception 75 and guidance of the film, as will be later explained.

Because of the flexible nature of the strips 21, 24, and 25, the toggles 18, the fingers 20, and the bars 22 and 23 may move toward the 80 center of the casing along radial lines in the collapsing of the telescopic arms 15 into the positions indicated by dotted lines in Fig. 1, approximately, the flexible strips 24 and 25 becoming looped between the adjoining supporting bars as indicated at 26 and which loops may fold down one over the other by 85 the pressure of the film thereon.

The outer sections of the telescopic arms 15 may carry perforated ears 27 adapted to 90 be engaged by hooks 28 on a button 29 normally held toward the front of the casing by means of a spring 30, this engagement of the said ears being automatic when the arms 15 are entirely collapsed with the film 95 wound thereon, but depression of the button 29 will release the arms 15 and permit the springs 16 therein to again extend the same.

By reference to Fig. 2 it will be noted that the channel 31 formed by the fabric strips 21, 24 and 25 is at an incline to the plane of the front and rear faces of the casing 5 and the forward end thereof is within the raised portion 6 whereas the rear end thereof is near the rear face of 105 the casing 5, thereby permitting the film at the forward end of said channel to clear the film already wound upon the telescopic arms 15.

In practice, the starting end of a film 110 after having been passed through a projector is threaded into the channel 31, now

in its outermost position, and the end of the film is then doubled around a roller 32 on carrier drum 11, Fig. 3, and locked in place by a slide 33, the film being upon the inner side of said carrier drum. As the drum 11 is revolved the film end engaged thereby is carried around the rollers 17 on the successive telescopic arms 15 and is continuously drawn through the channel 31 as it emerges from the projector and formed into successive layers, one within another, inside of the first turn which is held against the inner side of the carrier drum, and this continues until the entire film is within the magazine. As the successive film layers increase in number the arms 15 yield correspondingly until the entire film is wound thereon but it will be noted that the starting end of the film is at the outer surface of the reeled film ready for entrance into a projector without the necessity for reversely winding the same as is at present necessary.

The film is shown at 34 and when it is desired to thread the same into a projector the opening in the carrier drum 11 covered by the slide 33 is moved into register with an opening in the casing perimeter covered by a slide 35, the two slides then being opened and the film led out of the casing, the carrier drum not revolving at this time as will be understood, the reel of film revolving upon the rollers 17 of all of the arms, and I may, if desired, mount anti-friction rollers 36 in the drum and casing for the film.

Having fully described my invention, what I claim as new, and desire to secure by Letters Patent, is:

1. A magazine for a kinetoscope film,

comprising a casing, a carrier drum rotatable therein, means for attaching the end of the film to said drum, telescopic arms provided with rollers at their outer ends for the reception of the film, springs for normally maintaining said arms in extended positions, means for locking said arms in collapsed positions, and an inclined channel for guiding the film into said casing.

45

2. A magazine for a kinetoscope film, comprising a casing, a carrier drum rotatable therein, means for attaching the end of the film to said drum, telescopic arms provided with rollers at their outer ends for the reception of the film, a series of toggles arranged between two of said arms, fingers and bars carried thereby, and fabric strips carried by said fingers and bars forming an inclined channel for guiding the film into said casing, said strips being looped as the supporting bars are carried inwardly as said arms are collapsed by the accumulating film.

50

3. A magazine for a kinetoscope film, comprising a casing, a carrier drum rotatable therein, means for attaching the end of the film to said drum, telescopic arms provided with rollers at their outer ends for the reception of the film, a series of toggles arranged between two of said arms, fingers and bars carried thereby, fabric strips carried by said fingers and bars forming an inclined channel for guiding the film into said casing, and guide rods for said toggles, said strips being looped as the supporting bars are carried inwardly as said arms are collapsed by the accumulating film.
